UNITED STATES PATENT OFFICE.

THOMAS M. RIGGLE, OF OAKLAND, CALIFORNIA.

AUTOMATIC SPEED CONTROL FOR TRAINS.

Application filed August 17, 1922. Serial No. 582,407.

To all whom it may concern:

Be it known that I, THOMAS M. RIGGLE, a citizen of the United States, and a resident of Oakland, county of Alameda, and State 5 of California, have invented a new and useful Automatic Speed Control for Trains, of which the following is a specification.

My invention relates to means for automatically decreasing the speed of a train 10 when a "block" preceding the train is not in normal condition.

An object of the invention is to provide a speed control system which may be operated in part by pressure produced by the 15 motion of the train to place and hold the train brakes in applied position a length of time proportionate to the speed of the train when a block or track section preceding the train is not in normal condition.

Another object of the invention is to provide a speed control system of the character 20 described which may operate in connection with the engineer's brake-valve of the air-brake-system.

A further object of the invention is to provide means of the character described 25 which may be operated in conjunction with a source of electric power carried either on the train or along the track.

The invention possesses other objects and 30 features of advantage, some of which, with the foregoing, will be set forth in the following description of the preferred form of my invention which is illustrated in the drawings accompanying and forming part 35 of the specification. It is to be understood that I do not limit myself to the showing made by the said drawings and description, as I may adopt variations of the preferred form within the scope of my invention 40 as set forth in the claims.

Referring to said drawings:

Figure 1 is a view mostly diagrammatic of the means of my invention shown in connection with some of the associated portion 45 of the air-brake-system, tracks etc., the portion shown above the representation of the tracks being arranged to be carried on the train, whereas the portions indicated below and included between the tracks are adapted to be held in substantially fixed relation with respect to the tracks.

Figure 2 is a longitudinal sectional view 50 of the governing valve included in the apparatus.

Figure 3 is a view similar to Figure 1,

excepting that the source of electric power used in connection with the apparatus is associated with the track instead of being carried on the train.

As shown in Figure 1 of the drawings the track 2, comprising rails 3 and 4, is divided into the usual block sections, three of which are here shown and indicated by the numerals 5, 6 and 7 respectively. The portion 60 of the air-brake-system illustrated is of a well known type and is shown above the rail 3 since it is carried on the train. Included in the brake-system is the engineer's 65 brake-valve 9 connected to the air reservoir 12 by the reservoir pipe 13, and connected to the brake pipe 14 by the branch 15. As usually arranged the brake-pipe communicates with the distributing valve and the 70 triple valves on the cars of the train, the valves being caused to bring about the application of the brakes when the pressure in the brake-pipe decreases below a predetermined point.

The brake-valve is provided with a suitable control lever 17, several of the positions of which are indicated, viz, release, running, and service, the latter causing a reduction of the pressure in the brake-pipe and the consequent application of the brakes. In 75 the present embodiment of the invention the automatic control means cooperates with the brake-valve lever, and the means for actuating said lever is therefore fixedly positioned adjacent thereto. The lever actuating means 80 includes a cylinder 18 in which is reciprocally mounted a piston 19 provided with a rod 21 which extends through the cylinder head 22 and is adapted to releasably engage 85 the lever 17 so as to move it to service position.

Formed in the cylinder so as to lie on opposite sides of the piston in all of the positions thereof are ports 23 and 24 which by 90 means of the pipes 26 and 27 afford the cylinder communication with the reservoir and brake pipe respectively. The pipe 25 includes a feed valve 28 which normally maintains sufficient pressure in the cylinder chamber 29 associated with port 23, to exceed the pressure obtaining in the brake pipe. In this manner under normal conditions the piston-rod will be held entirely released from the control lever, and the latter 95 may be manipulated at will. However should the pressure in the chamber 29 be reduced below the brake-pipe pressure, the 100 105 110

piston-rod will be moved to place the lever in service position and an application of brakes will result.

In accordance with the foregoing, means are provided for causing a reduction in the pressure of the chamber 29 for a period proportionate to the speed of the train when a block or section preceding the train is not in normal condition. In other words under 10 the conditions mentioned said means will function to place the brakes in applied position and then hold them against release for a length of time dependent on the speed of the train. Communicating with the 15 chamber 29 such as by the pipe 31 which is connected to pipe 25 between said chamber and the feed valve, is a governor valve 32 whose operation is controlled by the condition of the track circuit preceding the train 20 and the speed of the train as it approaches said circuit. The governor valve as here illustrated comprises a cylinder 33 having a piston valve 34 mounted for reciprocation arranged therein. The latter is provided 25 with a piston 36, between the two sections of which is formed a chamber 37. Under normal track conditions, the piston valve will lie in such position as to cause the air entering the cylinder 33 from the pipe 31 to 30 be confined in the chamber 37; however when adverse conditions prevail the piston will be caused to assume a position wherein the chamber 37 will also be in communication with a port 39 open to the atmosphere, 35 thereby allowing of a reduction of the pressure in the chamber 29 and the consequent operation of the brakes. The piston valve is held in its normal position by a spring 41, and is fixed to an actuating piston 42 upon 40 which pressure is adapted to be exerted when track conditions are not normal so that the piston-valve will be moved against the compression of said spring to place the chamber 37 simultaneously in communication 45 with the chamber 29 and atmospheric port 39. Associated with the governor-valve is a blower or pressure device 43, the impeller 44 of which is preferably driven directly from one of the axles of the train such 50 as by a flexible shaft 46. In this manner the fluid pressure produced by the blower will invariably be in direct proportion to the speed of the train. As here shown the blower 55 casing 47 is formed integrally with the governor valve casing or cylinder 33, and the delivery chamber 48 of the blower opens directly upon the actuating piston 42; therefore for the purpose of simplicity the latter piston may be considered as operating within the said delivery chamber. With the 60 train traveling at the usual speeds, the pressure created by the blower will be sufficient to move the piston 42 and attached mechanism against the resistance of the spring 41. Means are therefore provided for allowing 65

the air to escape from the delivery chamber so as not to act upon the piston 42 when track conditions are normal. Preferably formed in the piston 42 is an opening 49 through which the air from the delivery 70 chamber may discharge into the atmosphere by way of perforations 51 and 52, respectively provided in the piston and cylinder 33. Cooperating with said opening is a valve 53 which when seated thereover prevents the escape of the air from the delivery chamber and causes the movement of the piston. The movement of the valve 53 is primarily controlled by an electro-magnet 54, the stem 55 of the valve being here arranged 75 to function as the magnet core. By means which will hereinafter be explained the magnet coil is adapted to be momentarily de-energized when the train approaches a track section which is not in normal condition. 80 In this manner assuming that conditions are such that the coil is demagnetized and the valve 53 thereby allowed to descend to its closed position, the air in the delivery chamber will be practically trapped and the pressure thereof will simultaneously rise and cause the piston 42 to be depressed whereupon the chamber 37 will be opened to the atmosphere. With the pressure in the chamber 29 thus allowed to reduce, the piston rod 95 21 will move to place the brake-valve lever in service position and the speed of the train will thus commence to reduce. As previously stated the magnet is but momentarily demagnetized, therefore the valve 53 will 100 return to its elevated open position as soon as the air pressure on the upper side of the valve decreases below the pull of the magnet coil on the core. When the valve is in closed position however, the only means of 105 exit of the air from the delivery chamber is through a comparatively small opening 56 formed in the wall of the delivery chamber. Furthermore it will be noted that the 110 walls of the delivery chamber are curved 115 so that the air will be deflected in a concentrated stream directly against the upper side of the valve. It will thus be clear that at whatever speed the train is traveling a proportionate resistance will be encountered by 120 the valve before it can return to its position and thereby relieve the pressure on the piston 42 sufficient to allow it to assume its elevated position; in other words the length of time which the piston rod 21 will hold the 125 brake-valve lever in service-position will depend upon the speed of the train. After the piston valve has been elevated so that the discharge of air from the chamber 37 is cut off and the pressure in the chamber 29 allowed to build up as governed by the feed-valve, the piston-rod will withdraw from 130 engagement with the brake-valve lever and the engineer may manipulate the latter at will. It will thus be clearly understood that 135

with the train approaching a section not in normal condition the train will be caused to reduce its speed, and only after said reduction actually takes place will the engineer be allowed to accelerate the speed of the train.

The electro-magnet which controls the movement of the valve 53 is arranged in a circuit 58 which is supplied with current from a suitable source such as the alternator 59 arranged in a separate circuit 61, the current being induced from the circuit 61 into circuit 58 by the transformer 62. Arranged in the circuit 58 is a switch 63 comprising a lever 64 having one arm weighted so as to normally hold the switch in closed position. Suitably arranged in each track section in fixed position with respect to the track is a magnet 66, here shown of the permanent type, which is adapted to act upon the lever 64 when the latter passes over it whereby the circuit 58 may be broken and the coil 57 de-energized. Associated however with the foregoing is means for preventing the de-energizing of said coil when the magnet opens the switch, if the track section preceding the train is in normal condition. Fixedly associated with each track magnet 66 is a pair of coils 67 and 68 arranged in a circuit 69. The latter is adapted to be held closed by a relay 71 arranged in a track circuit 72 associated with the block or track section next in advance of the section with which the particular magnet and coils are associated. It will be understood that the track-sections are insulated from each other, and that if a track section is clear the associated relay will hold closed the circuit 69 of the particular track-section with which it cooperates. Carried on the train and shunted across the magnet coil 57 and the transformer coil 62' respectively are induction coils 73 and 74, the latter of which it will be noted receives current continuously from the alternator 59. The coils 73 and 74 are positioned on the train in such manner that as the switch lever 64 passes a track magnet, said coils will respectively become aligned with the stationary coils 67 and 68, and thereby cause a current to be induced in the coil 73 and consequently produce a flow of current through the magnet coil 57.

As hereinbefore mentioned the embodiment illustrated in Figure 3 of the drawings is designed for allowing the main current for supplying the control system, to be associated with the track. As clearly shown, said embodiment includes a circuit 76 in which is arranged the magnet coil 57 and a battery 77 preferably of light capacity. Also arranged in said circuit is a switch 78 normally disposed in closed position similar to the switch 63 and adapted to be acted upon by a track magnet 79 in substantially the same manner as the track magnet 66 de-

scribed in connection with Figure 1. Thus as the switch 78 passes over the track magnet, the magnet-coil 57 will be de-energized. Means are also included, though somewhat different than that shown in Figure 1, for causing the coil 57 to remain energized providing the track section preceding the train is clear when the switch 78 is opened. Shunted across the switch 78 is a relay 81 normally disposed in open position and controlled by a circuit 82 provided with an induction coil 83. Associated with each track section is a circuit 84 which is adapted to be held closed when the train approaches a clear track section by the relay 86 of the track-relay-circuit 87 associated with a block or section in advance of the section with which the magnet 79 and circuit 84 are associated. Each of the circuits 84 is adapted to be supplied with current from a suitable feed line 88 through a transformer 89, and includes an induction coil 91 and a switch 92 which are respectively adapted to be aligned with the coil 83 and a magnet 93 carried on the train, while the switch 78 is passing over the track magnet 79. Assuming thus that the train is approaching a track section which is in normal condition, thereby causing the track-relay circuit to be closed, and that the coil 83, magnet 93, and switch 78 are respectively passing over the coil 91, switch 92 and track magnet 79, a current will flow through the circuit 84 by reason of the fact that the switch 92 is held closed by the magnet 93, and a current will be induced in the circuit 82 on account of the alignment of the coils 83 and 91. In this manner the relay 81 will close the circuit 76 and the magnet coil 57 will be energized notwithstanding the open position of switch 78.

It will be noted that if the train is traveling at a comparatively slow speed the control mechanism will not be operated since the port 56 will not allow the accumulation of pressure. In this manner the disadvantage of causing the brakes to be applied at slow speeds, which would in most instances cause the train to be brought to a complete standstill, is eliminated.

I claim:

1. In an automatic speed control for trains, the combination with a brake valve and a series of insulated track sections, of a magnet associated with one of said sections, means carried on the train arranged to be actuated by said magnet to place said brake valve in service position when one of said sections is not in normal condition, and means governed by the speed of the train for varying the length of time which said first means will hold said valve in service position. 120 125

2. In an automatic speed control for trains, the combination with a brake system and a series of track section, means 130

- carried on the train and actuated in part by a pressure produced by the motion of the train adapted to place and hold the brakes in applied position a length of time 5 proportionate to speed of the train when one of said sections is not in normal condition.
3. In an automatic speed control for trains, the combination with the brake-valve 10 of an air-brake system and a series of insulated track sections, and means carried on the train having a part actuated by a pressure produced by the motion of the train whereby said valve may be held in service 15 position a length of time proportionate to the speed of the train when one of said sections is not in normal condition.
4. In an automatic speed control for trains, the combination with the brake valve 20 of an air brake-system and a series of insulated track sections, magnets associated with said sections, and means carried on said train and actuated in part by a pressure created by the motion of the train arranged 25 to cooperate with said magnets and adapted to hold said valve in service position a length of time proportionate to the speed of the train when one of said sections is not in normal condition.
- 30 5. In an automatic speed control for trains, the combination with a series of track sections and the control lever of the brake-valve of an air-brake system, a magnet associated with each of said sections, 35 and means carried on the train and actuated in part by a pressure produced by the motion of the train arranged to cooperate with said magnets and adapted to place and to hold said control lever in service position 40 a length of time proportionate to the speed of the train when one of said sections is not in normal condition.
6. In an automatic speed control for trains, the combination with the brake-valve 45 of an air brake system and a series of insulated track-sections, a magnet associated with each of said sections, and means on the train arranged to be acted upon by one of said magnets to place said valve in service 50 position when one of said circuits is not in normal condition and having a part actuated by a pressure produced by the motion of the train whereby said valve will be positively held in said position a length of time 55 proportional to the speed of the train.
7. The combination with the control valve 60 of a brake-system for a train and a series of insulated track sections having electric circuits, magnets associated with said sections, mechanism adapted to be actuated by one of said magnets for moving said valve to service position when one of said circuits is not in normal condition, means included in said mechanism for retaining said valve 65 in said position a length of time proportional to the speed of the train, and means operative when said circuit is in normal condition for preventing the actuation of said valve operating means.
8. The combination with the control valve 70 of a brake-system for a train and a series of insulated track-sections having electric circuits, fluid pressure operated mechanism for moving said valve to service position, means for operating said valve moving mechanism having a pressure produced by the motion of the train and proportional to its speed, electrical means for causing said pressure means to function, and magnets 75 associated with said track-sections adapted to act upon said electrical means so as to cause said pressure means to operate when one of said track circuits is not in normal condition.
9. In an automatic speed control for 80 trains, the combination with the brake valve of a brake-system and a series of track-sections, a cylinder carried on the train, a piston in said cylinder adapted to be operatively associated with said valve, connections to said cylinder for normally maintaining such pressure on opposite ends of said piston as to cause the latter to be held inoperatively associated with the valve, mechanism communicating with said cylinder actuated by a fluid pressure produced by the motion of the train and proportional to the speed thereof adapted to vary the pressure in said cylinder at one 85 side of said piston a length of time proportional to said fluid pressure, and means associated with said track-sections adapted to cause said pressure mechanism to vary the pressure in said cylinder when one of said sections is not in normal condition.
10. In an automatic speed control for 90 trains, the combination with the brake-valve of a braking system and a series of track sections, a cylinder carried on the train, a piston in said cylinder adapted to be operatively associated with said valve, connections to said cylinder for normally maintaining such pressures in said cylinder on opposite sides of said piston as to cause the latter to be held inoperatively disposed with respect to said valve, and mechanism 95 communicating with said cylinder actuated by a fluid pressure produced by the motion of the train and proportional to the speed thereof adapted for effecting a variation of the pressure in the cylinder at one end of said pistons when one of said track-sections is not in normal condition whereby said piston will move said valve to service position.
11. In an automatic speed control for 100 trains, the combination with a brake valve of an air brake-system for trains and a series of insulated track sections, of a cylinder, a piston therein arranged to be connected to said valve, connec- 105
- 110
- 115
- 120
- 125
- 130

tions to said cylinder for normally maintaining an unequal pressure on opposite ends of said piston whereby the latter will be held inoperatively disposed with respect to said valve, a governor valve communicating with said cylinder at one end of said piston adapted in one position to vary the pressure in said portion of the cylinder whereby said piston will be moved to place 5
 10 said brake-valve in service position, a pressure producing device communicating with said valve and driven in accordance with the speed of the train adapted to move said governor valve to assume said position and
 15 maintain it a length of time proportional to the pressure produced by said device, electrically operating means adapted to normally prevent communication of said device with said valve, and magnets associated
 20 with said track-sections adapted to prevent said functioning of said electrical means when one of said track sections is not in normal condition.

12. In an automatic speed control for trains, the combination with the control lever of the brake-valve of an air brake-system for trains and a series of insulated track sections of a cylinder, a piston therein arranged to cooperate with said lever, connections from the brake-pipe and air supply of said system to said cylinder at opposite ends of said piston whereby the latter will be held inoperatively disposed relative to said lever, a governor valve associated with 25
 30 said supply connection adapted in one position to allow a reduction of the supply pressure in said cylinder whereby said piston will be moved to place said control lever in service position, a fluid-pressure device communicating with said governor valve arranged to produce a pressure in accordance with the speed of the train and adapted to move said governor valve to the position mentioned and cause it to be retained
 35 so a length of time proportional to the pressure produced, electrical means normally maintaining said governor valve out of the aforesaid position, and magnets associated with the track sections adapted to act upon
 40 45 said electrical means whereby the governor valve may assume said position when one of said track sections is not in normal condition.

13. In an automatic speed control for trains, the combination with the control valve of a braking system for trains and a series of insulated track-sections of fluid pressure operated means for placing and holding the control lever of said valve in service position, a device carried on the train for producing a fluid pressure in proportion to the speed of the train and provided with a delivery chamber, a governor valve for controlling the discharge of fluid 50
 55 60 65 from said means whereby said control valve

may be actuated as aforesaid and comprising a valve member arranged in said chamber and movable to allow or prevent the fluid discharge from said means, a valve controlling the discharge of fluid from said chamber and normally held in open position, and means operative to effect the closure of said valve when one of said track-sections is not in normal condition. 70

14. In an automatic speed control for trains, the combination with the control valve of a braking system for trains and a series of insulated track sections, of fluid pressure operated means for placing and holding the control lever of said valve in service position, a device carried on the train for producing a fluid pressure proportional to the speed of the train and provided with a delivery chamber, a governor valve for controlling the discharge of fluid from said means whereby said control valve may be actuated as aforesaid and comprising a valve member in said delivery chamber and movable to allow or prevent the fluid discharge from said means, a valve for controlling the discharge of fluid from said chamber, an electric circuit on the train, a magnetizing coil connected with said circuit and adapted to normally hold said last mentioned valve in open position, and magnets associated with said track-sections adapted to break said circuit and demagnetize said coil when one of said sections is not in normal condition. 80
 85
 90
 95

15. In an automatic speed control for trains, the combination with the brake valve of an air-brake-system and a series of track sections having substantially independent electric circuits, of a cylinder carried on the train, ports in said cylinder at opposite ends of said piston communicating respectively with the air reservoir and brake-pipe of said system, a valve associated with said supply port, an electric circuit provided with a source of current on the train, a magnetizing coil connected in said circuit and adapted to normally hold said valve in one position, a magnet associated with each track section adapted to open said last circuit whereby said coil may be de-energized, an induction coil in said circuit, circuits associated with each track section in addition to said first track circuits, a switch arranged in each of said additional track circuits adapted to be held in closed position by means of said first circuits when said track-sections are in normal condition, a source of electric supply for said additional circuits associated with said sections, induction coils in said latter circuits adapted to cooperate with said first induction coil when adjacent to each other, a second switch in each of said additional circuits normally held in open position, and a magnet carried on said train adapted to 100

close said second switch when adjacent thereto.

16. In an automatic speed control for trains, the combination with the brake valve of an air-brake-system and a series of insulated track-sections having substantially independent electric circuits, of a cylinder carried on the train, a piston in said cylinder adapted to operate the control lever of 10 said valve, ports in said cylinder at opposite ends of said piston communicating respectively with the brake-pipe and air-supply of said system whereby said piston will be normally held inoperatively disposed with respect to said control lever, a device for producing a fluid pressure proportional to the speed of the engine, a governor valve connected to said device and to said supply port for controlling the discharge of fluid 15 from said cylinder and comprising a valve member operating in the delivery passage of said pressure device and movable to allow or prevent the discharge of fluid from said cylinder whereby the position of said piston may be varied and said control lever moved accordingly, a valve for controlling the discharge of fluid from said delivery 20 passage, an electric circuit provided with a

source of current on said train, a magnetizing coil connected in said circuit and adapted to normally hold said last mentioned valve in one position, a magnet associated with each track section adapted to open said last circuit whereby said coil may be de-energized, an induction coil in said circuit, 30 circuits associated with each track-section in addition to said first track circuits, a switch arranged in each of said additional track circuits adapted to be held in closed position by means of said first track-circuits 35 when said track-sections are in normal condition, a source of electric supply for said additional circuits associated with said sections, induction coils in said latter circuits adapted to cooperate with said first induction coil when adjacent to each other, a second switch in each of said additional circuits normally held in open position, and a magnet carried on said train adapted to 40 close said second switch when adjacent 45 thereto.

In testimony whereof, I have hereunto set my hand at Oakland, this 11th day of August, 1922.

THOMAS M. RIGGLE.
